UNITED STATES PATENT OFFICE.

FRANK L. O. WADSWORTH, OF SEWICKLEY, PENNSYLVANIA.

GOLF-BALL.

1,182,605.

Specification of Letters Patent.

Patented May 9, 1916.

Application filed March 28, 1911. Serial No. 617,523.

To all whom it may concern:

Be it known that I, FRANK L. O. WADSWORTH, a citizen of the United States, residing at Sewickley, in the county of Allegheny and State of Pennsylvania, have invented a new and useful Improvement in Golf-Balls, of which improvement the following is a specification.

My invention relates to the construction 10 and manufacture of golf balls; and the particular object of this invention is the production of a golf ball which will have a high degree of elasticity, and will also have great carrying powers.

15 The further object of my invention is the production of a golf ball which will be comparatively inexpensive and will also be very durable in use.

In the drawings which form a part of 20 this specification Figure 1 is a cross-section of a golf ball constructed in accordance with my invention; Fig. 2 is a detail view showing a method of constructing the shell of the ball illustrated in Fig. 1; Fig. 3 is also 25 a sectional view of another ball embodying my invention; Fig. 4 is a sectional view of an apparatus which may be used in the construction of the balls shown in Figs. 1 and 3; Fig. 5 is a detail view illustrating one 30 manner of joining the parts of the metal shells of Fig. 4; Figs. 6 and 7 are cross-sectional views of other embodiments of this invention; and Figs. 8 and 9 illustrate a device for the construction of the ball 35 shown in Fig. 6.

The specific qualities which are of particular importance in golf balls are a high degree of resiliency, which will cause the ball to leave the head of the club with a 40 minimum loss of the energy imparted to it by the impact of the club head; accuracy of form and uniformity of mass distribution which will secure accuracy of play; an elasticity or elastic rigidity of form which 45 will resist distortion under severe use and the greatest possible carrying power which is in general obtained by the conservation of the rotative momentum resulting from the "spin" of the ball as it leaves the head of 50 the club. This conservation of rotative momentum or "spin" is dependent upon the distribution of material in the body of the ball. It will be the maximum when the mass of material is concentrated as closely 55 as possible to the outer surface. In order

that the golf ball may have carrying power it is also necessary that the ball have a certain weight, in order to give it enough momentum to avoid a too sudden checking of its flight by the resistance of the air. 60 The resistance of the air increases very rapidly with the velocity of the flight, and with the size of the ball. If the ball could be made very small and at the same time made very heavy and very resilient, the distance to which it could be driven through the air would be correspondingly increased. But the reduction of the size of the ball is limited by the conditions of play, which necessitate the use of a ball large enough to 65 be readily found and also large enough to enable it to be struck with the club head even when it is partially buried or covered by obstructions or irregularities on the course.

In the golf ball of ordinary construction the material used is rubber or gutta percha, which has a very high degree of resiliency, but which is of comparatively small density, and is also easily cut or distorted by the 70 blows of the club. Because of the low density of this material the ball must be made solid in order to obtain sufficient weight without undue increase in size, and consequently undue resistance of the air to 75 its flight. Making the ball solid greatly reduces its rotative momentum under a certain "spin," and correspondingly reduces the length of time during which this "spin" 80 will persist. As is well understood, it is the 85 effect of this "spin" which is largely responsible for sustaining the ball in the air and enabling it to be driven a long distance. It is evident, therefore that any construction 90 which will retain weight, resiliency, and 95 elastic rigidity of form and at the same time obtain a greater degree of rotative momentum, will correspondingly increase the length of such flight.

These objects are attained in my invention by constructing the golf ball with an outer shell composed in whole or in part of metal symmetrically disposed about the center of the shell, the mass of metal used 100 being such as to present a weight substantially equal to the weight of the present rubber or gutta percha balls. As the density of different metal varies from 9 to 13 times the density of rubber, and as the weight of a 105 spherical shell or layer of a given thickness 110

varies as the square of the diameter of that layer, it is possible to obtain by the use of comparatively small mass of metal concentrated at the outer surface of the ball, the same weight as is obtained by using a solid rubber sphere of the same external diameter. The concentration of the mass at the surface of the ball gives to that ball the maximum degree of rotary momentum under a given "spin," and thus enables me to attain both the maximum driving effect from the blow of the club and also the maximum carrying effect resulting from the persistence of the "spin" during the flight of the ball.

Referring now to the drawings Fig. 1 illustrates a golf ball in which I use a thin, highly tempered steel shell 1, as a basis for my improved construction. This shell is made preferably in two halves united by a lap joint, which can be brazed or welded so as to firmly unite the two parts.

The steel shell only 1/64 of an inch in thickness and 1-3/4 inches diameter will weigh nearly 1/2 as much as a solid rubber ball of the same external dimensions; and a steel plate of this thickness can be readily spun up or hot drawn to the required hemispherical shape. After having been shaped to the required form, a series of symmetrically and uniformly disposed holes are punched or drilled in each hemispherical half of the shell and it is next hardened and tempered in oil, the usual precautions being taken to prevent distortion of the parts during this operation. A series of buttons of some heavy dense metal, like lead or better Babbitt metal or brass are then secured to the steel hemispheres by riveting the shanks of these buttons into the holes of the shells, as shown in Figs. 1 and 2. A convenient method of doing this is shown in the latter figure which represents a portion of a hemispherical female die with holes 3, 3, drilled in its surface to receive the buttons 2, 2. The buttons are put in place in this die with the one half of the steel hemisphere 1, in position over them and are all riveted into the shell by a single stroke of the male die 4. The two halves of the shell are then secured together as before stated, and the exterior is covered with a layer 6 of rubber, gutta percha or leather molded preferably to conform to the button studded surface of the metal shell beneath, and cemented or vulcanized in place thereon in the usual manner. The hollow interior is then filled with air or gas under pressure through a suitable nipple opening in the manner illustrated in Fig. 4, and hereafter more fully described. In some cases however this external cover may be dispensed with and the metal simply covered with a protecting coating of paint or enamel.

In the construction illustrated in Fig. 3

the inner shell 7, is of heavy sheet rubber molded with a uniform and symmetrically disposed series of segmental cups or hollows in which are placed correspondingly shaped metal buttons, 8, 8, 8; the rubber shell and metal buttons being secured to each other by cementing or vulcanizing in the usual manner. The composite rubber metal shell is then slightly inflated through the hollow metal nipple 9, so as to give it a true spherical shape and it is then covered by a thin layer of copper, nickel or similar soft metal. This second soft metal shell, 10, may be formed in two halves, which are firmly united by interlocking the edges as shown in Fig. 5 and then filling the interstices of the joint, 11, with hard elastic cement, or with soft fusible metal, or with electro desposited copper. Or the inner composite shell may be covered with lamp black or with metal foil and then with a continuous homogenous sheet of electro deposited copper or nickel or copper and nickel so as to form a seamless metallic shell; which is completely closed except at the nipple opening 9, which is protected by a pin or plug. The outer cover 12 of leather, rubber or gutta percha is next applied to the shell, 10, and cemented or vulcanized thereto. A small opening 13, is left in this outer cover surrounding the nipple opening 9, through the two inner shells. The ball is then filled with air or gas at a high pressure, the opening, 9, hermetically sealed and the conical hole, 13, in the cover 12, filled in with a plug of material similar to that of which the rest of the cover is composed, this plug being likewise firmly cemented or vulcanized to the other parts of the ball. The pressure in the hermetically sealed interior is great enough to strain the soft metal shell, 10, to just about the elastic limit of the material of which it is composed. Under such circumstances this thin metal shell will become flexible and pliable and will readily follow the movements of the inner rubber shell and outer cover; the three combined layers of rubber, metal, and covering material, acting under the high pneumatic pressure within the ball, as a very resilient and highly elastic shell, which is at the same time sufficiently heavy to give the ball great driving and carrying power; much greater in fact than it would be possible to obtain with a solid rubber ball of the usual construction.

In Fig. 4 I show an apparatus which can be conveniently used in the final inflation and sealing of the balls constructed as above described. This apparatus consists of an air chamber, just large enough to contain a ball, covered by a removable cap, in the center of which is a stuffing box 15, through which is passed the stem of an electrically heated soldering iron, 16. A pipe 17 leads from the chamber, 14, to a three way cock,

18, by means of which the chamber may be put into communication with a source, 19, of compressed air or gas or with an exhaust opening 20. The ball is placed in the chamber, 14, with its nipple opening, 9, on top and held in position against accidental displacement in suitable spring clamps or other preferred form of support. The cap is then closed down and clamped in place and compressed air or gas admitted to the chamber through the cock 18. The cock 18, is then closed, the hot iron, 16, is depressed to solder up the nipple opening, 9, then raised again, and the cock, 18, opened. The inflated and sealed ball can then be removed from the chamber by opening the cap, another ball placed therein and the operation repeated.

In the construction shown in Fig. 6, I provide an inner plain spherical shell or ball 20 of sheet rubber, and cover this directly with an outer composite shell of metal and leather, or metal and gutta percha, 22, molded on the exterior to suitable form and provided on its interior with a series of uniformly disposed pockets, containing the metallic buttons, 23, 23, etc. This outer shell is preferably made in two parts, united at their meeting edges by sewing—if leather is used—or by vulcanizing, if gutta percha 30 is used, or in any other suitable manner. If desired a continuous band, 24, of spring steel or other highly elastic metal may be inserted between the joining edges of the outer cover to further stiffen the ball at this joint 35 and preserve the symmetry of weight distribution. Before applying the outer cover a triangular cut, 25, is made in the inner rubber shell, 21, and when the outer cover, 22, is put in place, a small inflation tube, 26, is 40 inserted through said cover so as to enter the opening, 25, and push back the flap of the cut as shown in Fig. 6. The ball may then be inflated and sealed in any desired manner, as for example, by means of the apparatus shown in Fig. 9. This apparatus is similar in general construction to that shown in Fig. 5 save that the soldering iron is replaced by a sealing tube which is made in three parts as best shown in cross-section in Fig. 8. The lower part 27 is provided with a taper socket to receive the shank of the inflation tube 26 and this is held in place by a snap catch which can be disengaged by a finger lever 29. Above 50 the socket is an enlarged central opening, 30, which communicates with the outside space through one or more openings, 31. The upper end of tube, 27, is internally threaded for the attachment thereto of the middle part, 32, which is also hollow and is closed at its upper end by the screw plug, 33. The lower end of the tube, 32, is prolonged downward into a feed nozzle, 34, which terminates just above the coned opening in the inflation tube, 26. The central chamber of the tube is

filled with rubber cement or equivalent material, which can be forced out through the nozzle, 34, by means of the screw plug, 33.

In the operation of filling and sealing the cap of the air chamber is thrown back, and the inflation tube and ball attached to the sealing tube, 27, in the manner indicated in Figs. 8 and 9. The cap is then closed and compressed air or gas admitted to the chamber and to the interior of the ball through the opening, 31, which communicates with the central opening in the inflation tube. After the pressure has become equalized on the inside and outside of the ball, the tube, 32, and its attached parts are lifted slightly 75 allowing the rubber flap of the cut, 25, to spring back toward its seat and a drop of rubber cement is forced out of the chamber, 34, by the screw plug, 33, so as to pass down through the bore of the inflation tube, 26, 80 and coat the interior surfaces of the opening, 25. A further withdrawal of the tubes, 32 and 26, allows this opening to be closed and a slight reduction in the external air pressure, automatically completes the sealing 85 of said opening by the action of the unbalanced internal pressure on the contacting edges of the cut. Instead of using cement to seal the joint 25, I may do this by using a strip, 35, of raw or uncured rubber, as 90 indicated by dotted lines in Fig. 6.

Instead of filling the inner chambers of the balls shown in Fig. 3 and Fig. 6 with compressed air or gas alone I generally prefer to fill them with the substance known 100 as "pneumastic" or a similar spongy or gelatinous compound introduced with air or gas under pressure after the ball has been made up as already described.

In the construction shown in Fig. 7 a core or filling 36 of some very light but preferably elastic material like block cork or compressed granulated cork or corn pith or similar substance, is first formed. This is coated on the exterior, preferably first 105 with a thin layer of pure sheet rubber, 37, and then with a layer of metal, 38. This layer of metal may be put on by electro deposition as before described, or it may be applied in the form of thin sheet foil or 110 wire wound in layers, or it may be applied as a granulated or powdered mass, mixed with rubber cement, or rubber solution. In all cases the mass of loading metal thus applied is somewhat less than in cases where 115 no core or filling is used, but the density of the core, 36, is so small that the greater part of the weight of the ball is concentrated in the metallic shell, 38. Then the outer cover, 39, of leather, gutta percha or 120 highly sulfurized rubber is put in place and the parts of the composite outer shell firmly united to one another by vulcanization in suitable spherical molds or in any other well known manner. In order to ob- 125

tain a pneumatic pressure on the interior of the ball, the core material, 36, may be mixed or impregnated with some chemical, which when heated to the temperature of 5 vulcanization will give off a sufficient volume of inert gas to produce the internal pressure required. This same plan of forming and charging the balls may be used with the constructions illustrated in Figs. 10 3 and 6.

It will be observed that in all of the constructions herein described, the necessary weight and rotative momentum of the ball is obtained by loading its outer periphery 15 with some heavy nonelastic metal, while the necessary resilience and elasticity is secured by supporting this metal mass by means of a resilient and highly elastic shell subjected to and reinforced by internal 20 pneumatic pressure. I prefer also to fill the interior of the shell with a core or filling of very light, spongy, elastic or semi-elastic material, such as pneumastic, granulated cork, corn pith or similar substance, 25 which will aid in preserving the form and shape of the outer composite shell, and in retaining the compressed air or gas without adding sensibly to the weight of the ball.

It will be further observed that my invention 30 involves the symmetrical distribution of the structural material about the center of the spherical surface so that the center of gravity of the ball coincides accurately and exactly with the center of figure. The 35 attainment of this result is of the utmost importance as the slightest deviation from coincidence of these two centers will cause the ball to "duck" or "dodge" in its line of flight through the air and to deviate from 40 the straight line of putt when playing on the greens. The provision of an accurately formed inner core or shell to support the loading weights and the outer cover of the ball and the reinforcement of this core or 45 shell by an internal pneumatic pressure is

of great assistance in attaining and maintaining this necessary symmetry of mass distribution both in the initial manufacture and in the subsequent use of the ball.

It is apparent that with this disclosure as 50 a basis other constructions embodying my invention may also be devised by those skilled in the art.

Having described my invention what I claim is:—

1. A golf ball having a relatively thin highly elastic and resilient shell, loaded with a heavy nonelastic mass of metal symmetrically disposed about the center of the shell and close to the outer surface thereof, 60 and a core or filling of very light nonmetallic material which forms a support for the said shell.

2. A golf ball having a relatively thin but highly elastic and resilient shell loaded 65 with a heavy nonelastic mass of metal which is symmetrically disposed about the center of the shell and close to the outer surface thereof, and a porous core or filling of very light nonmetallic material forming 70 a support for the outer shell and being charged with air or gas under considerable pressure.

3. A golf ball having a highly elastic and resilient shell containing a series of de- 75 pressed pockets projecting inwardly toward the center of the shell and filled with a heavy nonelastic metal the mass of which is symmetrically disposed about the center of the shell, the interior of the shell being 80 charged with air or gas under considerable pressure.

In testimony whereof I have hereunto signed my name in the presence of two subscribing witnesses.

FRANK L. O. WADSWORTH.

In the presence of—

CLARENCE A. WILLIAMS,
JOHN H. RONEY.
